US0D1084399S

(12) **United States Design Patent** (10) **Patent No.:** **US D1,084,399 S**
(45) **Date of Patent:** **** Jul. 15, 2025**

(54) **DOOR SEAL**

(71) Applicant: **Torsion Group Corp.**, Strongsville, OH (US)

(72) Inventor: **Kevin Wright**, Greenfield, IL (US)

(73) Assignee: **Torsion Group Corp.**, Strongsville, OH (US)

(**) Term: **15 Years**

(21) Appl. No.: **29/810,702**

(22) Filed: **Oct. 7, 2021**

(51) LOC (15) Cl. **25-01**

(52) U.S. Cl.

USPC **D25/48.2**; D25/119; D25/125

(57) **CLAIM**

The ornamental design for a door seal, as shown and described.

DESCRIPTION

FIG. 1 is a front-top-right perspective view of a door seal; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view thereof, wherein the door seal is shown in a folded configuration;

FIG. 9 is perspective view thereof, wherein the door seal is shown in a folded configuration and an installed environment;

FIG. 10 is a front elevational view thereof, wherein the door seal is shown in a folded configuration and an installed environment; and,

FIG. 11 is a front perspective view thereof, wherein the door seal is shown in a folded configuration and an installed environment.

The broken lines illustrate portions of the door seal as well as environmental structure which forms no part of the claimed design. The appearance of any portion of the door seal between the break lines shown in FIGS. 1-11 forms no part of the claimed design.
